UNITED STATES PATENT OFFICE.

JOHN FORDYCE BALFOUR, OF EDINBURGH, SCOTLAND.

APPARATUS FOR LOCALIZING THE EFFECT OF MINE EXPLOSIONS.

1,102,228.

Specification of Letters Patent.

Patented July 7, 1914.

Application filed July 5, 1912. Serial No. 707,795.

To all whom it may concern:

Be it known that I, JOHN FORDYCE BALFOUR, a British subject, residing at Portobello, Edinburgh, in the county of Midlothian, Scotland, have invented certain new and useful Improvements in Apparatus for Localizing the Effect of Mine Explosions, of which the following is a specification.

This invention has for its object, to reduce and localize the destructive effect of explosions in coal-mines, by establishing at suitable parts of the various galleries or levels devices for damping the roads, intercepting the rush of gases, or extinguishing the flames, which devices are called into action automatically by the pressure of the gases immediately after an explosion has occurred, and prevent the explosion or the poisonous gases from spreading to other parts of the mine. Such a device consists of two principal parts viz: a starting or primary operating device, which is situated as closely as possible to a locality, where explosions are liable to occur, and is set in action by any sudden increase of the normal gas or air pressure, or by the reversal of the air currents, and a secondary operating device, which may be situated in the same gallery or working as the primary or at a considerable distance from the same and is called into action by the operation of the primary device. The primary device may consist of a hinged flap or a cylinder and piston mounted in a lateral recess of the gallery or working, in such a manner that one side of the flap or piston is exposed to the pressure of the gases arising from an explosion, the said flap or piston being adapted to operate a wire or other transmission apparatus leading to the secondary device. The said secondary device may consist of a water pipe arranged on the sides, roof and bottom of the gallery or working and provided with slits for the discharge of water, a tap or valve controlling the flow of water to the said pipe under the influence of a weight or a spring, and a releasing mechanism, the whole being so arranged, that the said weight or spring tends to open the water passage, but is normally held back by a

catch or detent connected with the primary operating device, mechanically or electrically, so that the operation of the primary device will release the weight or spring, or act directly on the valve, after which the latter will rapidly open the passage supplying water to the outlets. The slits in the water discharge pipes are so arranged, that each slit projects a sheet of water directed obliquely toward the center of the gallery, and the different sheets form together the sides of a cone or pyramid, whose base is formed by the pipes and whose apex is directed toward the side, where the primary operating device is situated and where explosions are liable to occur.

In the accompanying drawings Figure 1 is a perspective view of an apparatus embodying this invention, Fig. 2 is a vertical section of an electrically controlled valve on a larger scale. Fig. 3 is a cross section of a water pipe along line A—B of Fig. 1, showing the slit for the discharge of water, Fig. 4 is a horizontal section of a primary device consisting mainly of a pair of flap doors, Fig. 5 is a vertical section showing on a larger scale a mercury-contact apparatus adapted to be operated by a flap or piston. Figs. 6 and 7 show a modification of one of the flap doors shown in Fig. 4, Fig. 7 being a horizontal section and Fig. 6 an elevation; Figs. 8 and 9 represent a modification of the water pipe shown in Fig. 3; Fig. 10 is a vertical section through a pair of water discharge pipes mounted in a gallery; Fig. 11 shows a modification of the mercury contact device shown in Fig. 1.

a is a board mounted on the wall of a gallery close to a place, where explosions are liable to occur. The said board carries at the top a movable flap b and a U-shaped glass tube c containing mercury. Into one end of the said tube extends an arm d connected with the flap b in such a manner, that, if the latter is caused to turn on its horizontal axle by an explosion, the arm d will descend into the mercury and thereby close the electric circuit, of which the two wires e and f form a part. The said circuit includes a solenoid g, the core h of which

is connected with a lever *i* forming part of the valve-operating mechanism Fig. 2. On the axle of the lever *i* is mounted a segment *k* which presses on the head of a valve spindle *l*, pressed upward by a helical spring *n*.

In the normal position shown by Fig. 2 the valve *m* closes the water passage *o*, but if the circuit of the solenoid *g* is closed, the 10 lever *i* is drawn down, causing the segment *k* to turn into the position shown by dotted lines, and allowing the spring *n* to lift the valve *m*. Water now flows from the main supply pipe *p* and the branch pipe *o* into the pipe *q*, which surrounds the gallery and has a slit *r*, from which the water escapes in 15 the shape of a pyramid.

In Fig. 4, which shows another form of the primary device, *s* and *s'* are the two 20 wings of a flap door mounted on a vertical axle along the wall of a gallery. The upper and lower bearings of the said axle are held in a box-frame *t* mounted in a recess formed in the wall of the gallery. If a sudden 25 rush of gases caused by an explosion takes place in the direction of the arrow, the gases will turn the large wing *s* inward, causing the small wing *s'* to turn into the position indicated by dotted line. The further motion of the door is prevented by the 30 contact of the wing *s* with the stop *t'* formed on the frame *t*. The wing *s'* is connected by a wire *u* with a bolt *v* forming part of the contact device shown in Fig. 5 and preferably 35 mounted in the box *t*. When the said bolt is drawn by the motion of the wing *s'*, the piston *w* previously held by the bolt drops into the mercury cup *x* and closes the 40 circuit of an electric current passing through the wires *e* and *f*.

As indicated by Figs. 6 and 7, the small wing *s'* may have a suitable number of openings (louvers *S'*) covered with flaps *S*, adapted to open if the pressure of the gases 45 exceeds a given limit, and subsequently to close again by their own weight.

If desired, each water discharge pipe may have two or more parallel slits *r* and *r'*, as indicated by Figs. 8 and 9, or two or more 50 parallel pipes may be mounted at a short distance apart, so that the sheets of water discharged by the pipes will form two or more cones or pyramids placed one behind the other. This modification is illustrated 55 by Fig. 10, where *q* indicates the discharge pipes provided with slots *r*.

For electrical connection the primary device may consist of a U-shaped glass tube *y*, Fig. 11 partly filled with mercury and sealed 60 at one end, the open end of the tube being exposed to the pressure of the air or gases, while the other leg of the tube contains the end of a wire *z* serving to make electric contact with the mercury, when the latter is

forced up by an increase of air pressure. 65 The said wire forms the terminal of an electric circuit including the wires *e* and *f* and adapted to operate an electromagnet forming part of the secondary device.

What I claim is:—

1. Apparatus for localizing the effects of explosions in mines, comprising a primary operating device mounted in a locality where explosions are liable to occur and adapted to be set in motion by a sudden change of 75 air-pressure, a system of water discharge pipes surrounding a section of a gallery situated at a distance from the primary apparatus and provided with narrow water-outlets directed toward the center of the gallery, a water-supply pipe communicating with the said water discharge-pipes, a valve interposed between the said water supply-pipe and water-discharge-pipes, and means 80 adapted to operate the said valve under the influence of the said primary device, substantially as described.

2. In apparatus for localizing the effects of mine-explosions, the combination of a primary operating device mounted in a locality where explosions are liable to occur and adapted to be set in motion by a sudden change of pressure in the said locality, with a system of water discharge-pipes surrounding a section of a gallery at a distance 95 from the same, and having slits arranged so as to project sheets of water toward the center of the gallery in the direction of the said primary device, a water-supply pipe communicating with the said water discharge pipes, a valve interposed between the water supply pipe and the water discharge pipes, and means for operating the said valve under the influence of the said primary device, substantially as described. 100

3. In apparatus for localizing the effects of mine explosions, the combination of a system of water discharge pipes surrounding a section of gallery and having narrow outlets directed toward the center of the gallery, with a water supply pipe communicating with the said discharge-pipes, a valve interposed between the water-supply-pipe and the discharge pipes, a spring adapted to open the said valve, a locking device adapted to act on the said spring so as to keep the valve in the closing position, and an electromagnet adapted to set the said locking device out of action, substantially as described. 110

4. In apparatus for localizing the effects 120 of explosions in mines by means of a primary operating device mounted in a locality where explosions are liable to occur and adapted to be set in motion by a sudden change of air pressure, a primary operating 125 device consisting of a pair of flap-doors, mounted opposite each other in lateral recesses of a gallery, each flap-door having a

pair of wings placed at an angle to each other and adapted to turn on a vertical axis at the side of the gallery, one wing being movable in a recess of the gallery under the influence of gas-pressure, and the other wing being adapted to close the adjacent half of the gallery, substantially as described.

In testimony whereof I have hereunto set my hand in presence of two subscribing witnesses.

JOHN FORDYCE BALFOUR.
